Primary Examiner—Holly H Bayham*Assistant Examiner*—Cynthia M Chin(74) *Attorney, Agent, or Firm*—Alix, Yale & Ristas LLP(57) **CLAIM**

The ornamental design for a toy spy sleeve, as shown and described.

DESCRIPTION

FIG. 1 is a perspective view of a toy spy sleeve showing my new design;

FIG. 2 is a bottom plan view thereof;

FIG. 3 is a left side elevational view thereof;

FIG. 4 is a right side elevational view thereof;

FIG. 5 is a top plan view thereof;

FIG. 6 is front elevational view thereof;

FIG. 7 is a rear elevational view thereof; and,

FIG. 8 is a top plan view in open position thereof.

The broken lines in the figures are for illustrative purposes only and form no part of the claimed design.
